Assistant Examiner — Cole Sanders Holman

CLAIM

The ornamental design for a mobile scan apparatus, as shown and described.

DESCRIPTION

FIG. 1 is a front perspective view of a mobile scan apparatus, showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The dashed broken lines in FIGS. 2 and 4-7 depict portions of the mobile scan apparatus that form no part of the claimed design.

1 Claim, 7 Drawing Sheets
